LOOSE LEAF BINDER

Adolph G. Lotter, Milwaukee, Wis., assignor to
 Stationers Loose Leaf Company, Milwaukee,
 Wis., a corporation of Wisconsin

Application November 6, 1933, Serial No. 696,823

19 Claims. (Cl. 129—4)

This invention relates to loose leaf binders and refers more particularly to binders of the split ring type.

As is well known, it has always been difficult in ring binders, to prevent tearing the leaves as a result of the binding effect between the rings and the leaves during closing of the binder. Many different devices have been proposed to eliminate this binding effect and thereby facilitate closing of the binder, but not any of the schemes heretofore proposed attained the desired smoothness of operation.

In nearly all instances, a sheet follower sometimes termed a "leaf flipper" has been employed. These followers generally consisted of stiff plate-like members provided with apertures to receive the rings of the binder, and extended a few inches toward the free ends of the covers to provide rigid supports for the leaves during closing of the binder.

To these followers or leaf flippers, devices were added to improve the functioning thereof, but as hereinbefore noted, these past expedients have all fallen short of attaining the desired degree of smoothness of operation and assurance against tearing the leaves.

With these objections to existing devices of the character described in mind, this invention has as an object to provide a new and improved type of follower which is so constructed and associated with the binder as to produce a new motion throughout the entire range of closing movement of the binder, by which binding between the leaves and the rings is entirely eliminated.

A further object of this invention is to provide a follower device which is readily adaptable to different types of ring binders and which may be supplied as a separate unit to be installed in binders already in use.

More specifically, it is an object of this invention to provide a follower device for ring binders in which the two sheet supporting elements are hingedly connected and constrained to swing about an axis near the center of the rings.

With the above and other objects in view which will appear as the description proceeds, my invention resides in the novel construction, combination and arrangement of parts substantially as hereinafter described and more particularly defined by the appended claims, it being understood that such changes in the precise embodiment of the herein-disclosed invention may be made as come within the scope of the claims.

In the accompanying drawings, I have illustrated two complete examples of the physical

embodiment of my invention constructed according to the best modes I have so far devised for the practical application of the principles thereof, and in which:

Figure 1 is a perspective view of a ring type loose leaf binder illustrating the application of this invention thereto; 5

Figure 2 is an end view with parts broken away and in section of the binder and follower shown in Figure 1, in closed position; 10

Figure 3 is a detail perspective view of one of the supports for the hinge connection between the follower elements; 15

Figure 4 is a perspective view similar to Figure 1 illustrating a modified embodiment of this invention applied to another type of ring binder; 20

Figure 5 is an end view of the binder and follower shown in Figure 4;

Figure 6 is a detail perspective view showing part of the back of the binder illustrated in Figures 4 and 5, and showing the position of the hinge support thereon; 25

Figure 7 is a top plan view showing one end of a visible record loose leaf binder in open position equipped with the follower device of this invention; 30

Figure 8 is a view similar to Figure 7 but illustrating the binder in its open position with its ring sections staggered; 35

Figure 9 is an end view of the visible record binder shown in Figures 7 and 8 in closed position;

Figure 10 is a detail section view taken through Figure 8 on the plane of the line 10—10; 35

Figure 11 is a perspective view of a small capacity binder with a modified form of the invention applied thereto; and

Figure 12 is an end view of the binder shown in Figure 11 in closed position. 40

Referring now more particularly to the accompanying drawings in which like numerals indicate like parts throughout the several views, the numeral 5 designates generally the back of a loose leaf ring binder which may be built up of superimposed elements, the detailed construction of which forms no part of this invention. Hingedly connected to the opposite sides of the back 5 are covers 6.

In the particular binder illustrated in Figures 1 and 2, the back 5 mounts two ring carrying plates 7, which are guided for sidewise motion toward and away from each other, effected by shifting an actuator bar 8 longitudinally, one way or the other. The transversely shiftable 55

plates 7 carry complementary impaling prongs, which, together form retaining rings 9 to removably hold a plurality of leaves 10 indicated in construction lines in Figure 2.

5 The followers, which form the subject matter of this invention, in the embodiment illustrated in Figures 1 and 2, consist of two substantially flat plates 11 having right angularly disposed flanges 12 at their adjacent inner edges. The flanges 12 may be formed as integral parts of the plates 11 or may be separate elements riveted or otherwise secured thereto. The upper free edges of the flanges 12 have complementary curled loops 13 to receive a hinge pin 14. The 10 two followers are thus hingedly connected.

To accommodate the rings 9, the plate members 11 have elongated apertures 12', and to provide a smooth sliding engagement between the outer free edges of the plate members and the 15 covers, the plate members are formed with rounded ribs 15. The ribs 15 also stiffen the plate members as will be readily apparent.

It is observed from Figure 1 that when the 20 binder is open, the axis of the hinge connection between the two followers is near the center of the rings, and to maintain the same centrally located throughout the closing movement of the binder and also when the same is closed, and to hold the followers off the rings, supports 16 are 25 provided for the hinge connection. These supports, as illustrated in Figure 3, may be conveniently formed by a single strip of bendable metal bent to substantially inverted T shape, with oppositely extending feet 17 to rest on the 30 top of the back, and an upstanding central stem 18 having an elongated loop 19 at its upper end. The looped upper end 19 is received in openings 20 cut in the upstanding flanges 12 of both followers, and the hinge pin 14 passes through 35 the loop.

The loop is elongated as illustrated to permit the hinge pin to float vertically. This vertically floating support or anchor for the hinge pin is especially important in large capacity binders as 40 it precludes binding and bulging of the leaves when the binder is completely closed.

In the modification illustrated in Figures 4, 45 5 and 6, the binder as well as the follower is of slightly different construction. The binder in 50 this instance is of the snap ring type in which the ring sections are spring held in either closed or open position by means (not shown) mounted within the back member 22. The covers 6 are 55 connected to the back member through an auxiliary back member 23, and handles 24 are provided to facilitate opening the ring sections.

The followers, as in the embodiment illustrated in Figures 1 and 2, consist of flat plate members equipped with the ribs at the outer edges thereof 60 to afford a smooth sliding engagement with the covers, and openings for the rings. Short up-standing right angular flanges 25 are formed at their inner edges, and fixed to the short up-standing flanges are angularly bent flanges 26, 65 the outer free edges of which are hingedly connected as at 27.

As in the embodiment hereinbefore described, supports are provided to hold the hinge connection near the center of the rings, and as before, 70 these supports are conveniently formed from a length of bendable metal bent to substantially inverted T shape. The upper looped ends of the supports which receive the hinge pin, project through openings 28 in the flanges 26. The lower portions 17' instead of merely resting on the top 75

of the back, have their outer ends bent over the opposite sides of the back member as at 29 so that the supports are rigidly attached to the back member and held against sidewise shifting with respect thereto.

The attachment of the supports to the back member, however, does not interfere with the slightly floating mounting for the followers and does not introduce any possibility of binding.

In Figures 7 to 10 inclusive, the application of 10 this invention to a visible record binder is illustrated. The binder shown in these views is of 15 that type in which the rings are composed of two series of complementary impaling prongs 30 and 31. The prongs 30 are carried by a plate 32 15 and the prongs 31 are mounted on a plate 33. These two prong carrying plates are mounted for 20 simultaneous sidewise movement toward and from each other on the back 34 of the binder and are adapted to be locked against separation by a longitudinally shiftable locking bar 35. Upon release effected by shifting the bar 35, the prong carrying plates may be shifted toward and from 25 each other, and to facilitate such sidewise shifting, handles 36 are provided.

The plate 33, which carries the series of prongs 31, besides being shiftable laterally is also shiftable longitudinally half the distance between the prongs to stagger the prongs 31 with respect to the prongs 30. The manner in which the plates 32 30 and 33 which carry the prongs are mounted on the back forms no part of this invention and has, therefore, not been shown in detail.

It is noted, however, that the plates 32 and 33 have opposed tongues 37 at their adjacent edge 35 portions adapted to overlie the longitudinally shiftable locking bar 35 when the binder is in closed position.

The followers in this embodiment of the invention are in many respects similar to those illustrated in Figures 4 and 5, differing therefrom principally in the fact that the hinge connection accommodates relative endwise shifting between the two followers, this being accomplished by leaving spaces 38 between the loops of the hinge 45 connection.

The followers are also notched to receive the tongues 37 when the prong carrying plates are separated, and through the engagement of the tongues in the notches, the followers are held 50 against endwise shifting with respect to their respective prong carrying plates. Hence, upon longitudinal shifting of the prong carrying plate 33, its follower moves in unison therewith.

The hinge connection 27 in this instance is 55 yieldably held in its uppermost position and to this end, the hinge pin passes through elongated vertical slots 39 in upstanding posts 40 fixed to the locking bar 35. Compression springs 41 are 60 confined between the hinge pin and barriers in the bottom of the posts conveniently provided by cross pins 42. The flanges 26 of the followers are cut away sufficiently as at 43 to accommodate the movement of the posts 40 with the locking bar.

Another very simple embodiment of the invention is illustrated in Figures 11 and 12. This form of the invention is particularly applicable to small capacity binders. The major distinction over the other modifications resides in the manner in which the hinge axis is supported from the back of the binder during operation.

The two followers 11' are connected by two small hinges 45 having right angular flanges 46 to which the followers are riveted as at 47. Open- 75

ings 48 in the followers receive the impaling prongs 9 of the binder.

Formed on the inner edge of each follower are extensions 49 and recesses 50, the extensions 49 of one follower being opposite the recesses of the other follower. The extensions are of such length that during opening and closing of the binder, they ride on the inner curved face 51 of the back of the binder and thus support the hinge axis at a point near the common center of the rings. The support for the hinge axis is provided as an integral part of the followers themselves, thus obviating the necessity for additional supporting units.

15 As will be readily apparent, when the binder is fully open, the fact that the extensions on the followers enter recesses in the opposite follower, permits the followers to lie flat.

From the foregoing description taken in connection with the accompanying drawings, it will be readily apparent to those skilled in the art, that this invention affords novel and improved followers for ring type loose leaf binders, and that by reason of the fact that the two followers are 20 hingedly connected and that their hinge connection is maintained somewhere near the center of the rings or at least above the back, the portions of the followers adjacent the rings are lifted a substantial distance during the initial closing 25 movement of the covers.

This substantial upward lifting movement of the followers effectually prevents binding of the leaves on the rings, and as the followers at no time ride on the rings, the optimum of smooth action is realized.

30 It is also apparent that the followers may be made as separate articles of manufacture to be supplied in sets readily applicable to binders already in use, especially that type illustrated in Figures 1 and 2, and 11 and 12.

What I claim as my invention is:

1. In a loose leaf binder including covers and rings to hold a plurality of leaves, followers disposed between the covers and the outermost leaves 45 and adapted to support the leaves as the binder is closed, and means to hingedly connect the followers with each other to constrain the same to a predetermined motion.

2. In a loose leaf binder including rings to retain a plurality of leaves and covers associated with the rings, followers connected with the rings and disposed between the covers and the outermost leaves, and common means to connect the inner portions of the followers and constrain their motion during opening and closing of the binder to a swinging movement about an axis lying near the center of the rings so that the followers at their portions adjacent the rings are lifted a substantial distance from the covers to smoothly carry the leaves about the rings during closing of the binder.

3. In combination with a loose leaf binder having covers and rings to retain a plurality of leaves, followers between the covers and the outermost leaves to carry the leaves around the rings and facilitate closing of the binder, said followers comprising substantially flat body portions with upstanding flanges at their inner edges, and means to hingedly connect the upstanding flanges.

4. As an article of manufacture, a set of followers for loose leaf binders of the ring type comprising, a pair of substantially flat plate members, flanges extending upwardly from the plate

members adjacent their inner edges, and means to hingedly connect said flanges.

5. As an article of manufacture, a set of followers for loose leaf binders of the ring type comprising, a pair of substantially flat members having apertures in their adjacent portions to receive the rings of a binder, upstanding walls at the adjacent portions of said members, and means hingedly connecting the upstanding walls of the two flat members.

10 6. In combination with a loose leaf binder of the ring type, a pair of followers comprising two substantially flat members having angularly disposed flanges at their adjacent edges, loops at the outer edges of said flanges, and a hinge pin 15 extending through said loops to provide a hinged connection between said substantially flat members, and said flat members having apertures to receive the rings of the binder.

7. In combination with a visible record loose 20 leaf binder having sheet retaining rings composed of two series of complementary impaling prongs mounted for movement apart and one of said series being shiftable to stagger the prongs, followers to facilitate closing of the binder, said 25 followers having apertures to receive the prongs, and means to hingedly connect the adjacent portions of the followers, said hinged connection permitting relative endwise shifting of said followers so as to accommodate the shifting of said one 30 series of prongs.

8. In a loose leaf binder including a back, covers hingedly connected with the back and rings carried by the back to retain a plurality of leaves, followers disposed between the covers and 35 the outermost leaves, a hinged connection between the followers, and means to hold the hinged connection in a position with the axis thereof near the center of the rings, said means permitting a limited degree of movement of the hinged 40 connection toward and away from the back during opening and closing of the binder.

9. In a loose leaf binder having covers and rings to retain a plurality of leaves, angle plates, hinge means connecting the adjacent flanges of 45 said angle plates, and a substantially floating support to hold the hinge connection near the common center of the rings, said angle plates being perforated to accommodate the rings, whereby the remaining flanges of the angle plates may 50 be disposed between the covers and the outermost leaves to support the leaves and facilitate closing of the binder.

10. As an article of manufacture, a set of followers for loose leaf binders of the ring type comprising, a pair of substantially flat plate members, means hingedly connecting the plate members, and means carried by the plate members and engageable with a binder part to support the plate members during opening and closing of the 60 binder and maintain the hinge axis near the common center of the rings.

11. As an article of manufacture, a set of followers for loose leaf binders of the ring type comprising, a pair of substantially flat members having apertures in their adjacent portions to receive the rings of a binder, means to hingedly connect the adjacent portions of the flat members, said means positioning the hinge axis inwardly of the planes of the two flat members so that when the 70 binder is open and the flat members lie in substantially a common plane, the hinge axis is located near the common center of the rings of the binder, and means carried by the flat members and engageable with a binder part to support 75

the flat members during opening and closing of the binder and hold the hinge axis near said common center of the rings.

12. As an article of manufacture, a set of followers for loose leaf binders of the ring type comprising, a pair of substantially flat members having apertures in their adjacent portions to receive the rings of a binder, means to hingedly connect the adjacent portions of the flat members, said means positioning the hinge axis inwardly of the planes of the two flat members so that when the binder is open and the flat members lie in substantially a common plane, the hinge axis is located near the common center of the rings of the binder, and extensions on the adjacent portions of the flat members engageable with a binder part during opening and closing of the binder to maintain the hinge axis substantially near the common center of the binder rings.

13. As an article of manufacture, a set of followers for loose leaf binders of the ring type comprising, a pair of substantially flat members having apertures in their adjacent portions to receive the rings of a binder, means to hingedly connect the adjacent portions of the flat members, said means positioning the hinge axis inwardly of the planes of the two flat members so that when the binder is open and the flat members lie in substantially a common plane, the hinge axis is located near the common center of the rings of the binder, and extensions on the adjacent portions of the flat members engageable with a binder part during opening and closing of the binder to maintain the hinge axis substantially near the common center of the binder rings, each of said flat members having a recess opposite an extension on the other flat member to receive such extension when the binder is open and the flat members lie in substantially the same plane.

14. In combination with a loose leaf binder having covers connected by a back and rings to retain a plurality of leaves, followers between the covers and the outermost leaves, means to hingedly connect the followers, and extensions on the followers adapted to ride on the back of the binder during opening and closing of the binder to support the followers and maintain the hinge axis spaced from the back of the binder.

15. The combination with a loose leaf ring binder adapted to accommodate a sheaf of loose leaf sheets, of a pair of rigid strips each of which comprises an inner arm and an outer arm perpendicular thereto, said strips being hinged together at the ends of the inner arms, the hinge being substantially aligned with the axis of the binder rings, and the outer arms overlying the binder covers, respectively, and means for maintaining said hinge substantially in said alignment with the ring axis when the covers are brought into parallelism to close the binder, whereby when the binder is closed the inner arms will engage the rear edge of said sheaf and bring the sheets into parallel relationship.

16. The combination with a loose leaf ring binder adapted to accommodate a sheaf of loose leaf sheets, of a pair of rigid strips each of which

comprises an inner arm and an outer arm perpendicular thereto, said strips being hinged together at the ends of the inner arms, the hinge being substantially aligned with the axis of the binder rings, and the outer arms overlying the binder covers, respectively, and means carried by said strips for maintaining said hinge substantially in said alignment with the ring axis when the covers are brought into parallelism to close the binder, said means bracing against a portion of the binder during the closing operation, whereby when the binder is closed the inner arms will engage the rear edge of said sheaf and bring the sheets into parallel relationship.

17. The combination with a loose leaf ring binder adapted to accommodate a sheaf of loose leaf sheets, of a pair of rigid strips each of which comprises an inner arm and an outer arm perpendicular thereto, said strips being hinged together at the ends of the inner arms, the hinge being substantially aligned with the axis of the binder rings, and the outer arms overlying the binder covers, respectively, and means for maintaining said hinge substantially in said alignment with the ring axis when the covers are brought into parallelism to close the binder, said means comprising a rigid abutment carried by the binder and adapted to be encountered by the hinge during the closing operation, whereby when the binder is closed the inner arms will engage the rear edge of said sheaf and bring the sheets into parallel relationship.

18. The combination with a loose leaf ring binder adapted to accommodate a sheaf of loose leaf sheets, of a pair of rigid strips each of which comprises an inner arm and an outer arm perpendicular thereto, said strips being hinged together at the ends of the inner arms, the hinge being substantially aligned with the axis of the binder rings, and the outer arms overlying the binder covers, respectively, each of said strips having a longitudinal slot permitting application of the device to the binder in interengagement with one of the rings, and means for maintaining said hinge substantially in said alignment with the ring axis when the covers are brought into parallelism to close the binder, whereby when the binder is closed the inner arms will engage the rear edge of said sheaf and bring the sheets into parallel relationship.

19. In a loose leaf binder including a back, covers hinged to the back and rings to hold a plurality of leaves, followers disposed between the covers and the outermost leaves, said followers having upstanding parts at their inner edges, means for hingedly connecting the outer edges of the upstanding parts, said upstanding parts projecting up from the inner surfaces of the followers a distance such that when the binder is open and the followers are in substantially horizontal alignment the hinge axis is located a substantial distance up from the back of the binder and close to the center of the rings, and means to support the hinge axis at a point near the center of the rings during closure of the binder.

ADOLPH G. LOTTER.
